Primary Examiner — Barbara Fox(74) *Attorney, Agent, or Firm* — Whitmyer IP Group LLC(57) **CLAIM**

The ornamental design for a display screen or portion thereof with graphical user interface, as shown and described.

DESCRIPTION

FIG. 4.1 is an isometric view of the display screen or portion thereof with graphical user interface showing the new design.

FIG. 4.2 is a front view thereof.

FIG. 4.3 is an enlarged portion thereof of the portion indicated in FIG. 4.1.

The evenly-spaced broken lines showing the device in FIG. 4.1 illustrates environment and forms no part of the claimed design. The remaining evenly-spaced broken lines in FIGS. 4.1, 4.2, and 4.3 illustrate the display screen or portion thereof with graphical user interface and form no part of the claimed design. The unevenly-sized broken lines in FIGS. 4.1 and 4.3 illustrate an enlargement and form no part of the claimed design.
